UNITED STATES PATENT OFFICE.

JOHN H. ANDREWS, OF NEW YORK, N. Y.

DESIGN FOR A BIRD-CAGE.

SPECIFICATION forming part of Design No. 21,569, dated May 24, 1892.

Application filed April 27, 1892, Serial No. 430,915. Term of patent 7 years.

To all whom it may concern:

Be it known that I, JOHN H. ANDREWS, a citizen of the United States, residing at New York city, New York, have invented a new and 5 original Design for Bird-Cages, of which the following is a specification, reference being had to the accompanying drawings, which form a part of the same.

The invention relates to a design for bird- 20 cages; and it consists of a new shape or configuration of a bird-cage.

My invention is represented in the accompanying drawings, in which—

Figure 1 is a front elevation, and Fig. 2 a 15 horizontal section on the line 2 2, Fig. 1, of a bird-cage embodying my design.

The characteristic feature of my design consists of an extension *a*, resembling a bay-window, projecting from one end of the cage.

My design also includes an inclined board 20 *b*, projecting from the cage and provided with a somewhat chariot-shaped feed-box *c*, mounted on wheels thereupon.

What I claim as my invention is—

The design for bird-cages, consisting of the 25 design substantially as shown.

JOHN H. ANDREWS.
